[57] CLAIM

The ornamental design for a water still, as shown.

DESCRIPTION

FIG. 1 is a perspective view taken from the top, one side and one end of a water still showing my new design;

FIG. 2 is a perspective view taken from the top and side and end opposite those shown in FIG. 1;

FIG. 3 is a top plan view thereof;

FIG. 4 is an elevational view taken from the side shown in FIG. 1;

FIG. 5 is an elevational view taken from the end shown in FIG. 2;

FIG. 6 is an elevational view taken from the side shown in FIG. 2; and

FIG. 7 is an elevational view taken from the end shown in FIG. 1.

Fig. 1.

Fig. 2.
